UNITED STATES PATENT OFFICE

MARLIN S. CROSSLEY, OF OKLAHOMA CITY, OKLAHOMA

ROTARY ENGINE

Application filed April 9, 1930. Serial No. 442,833.

This invention relates to improvements in internal combustion engines of the rotary type and embodying a stator unit and a rotary unit, and the invention has as one of its objects to provide a novel arrangement of the cylinders of the rotor unit and the pistons thereof together with a novel arrangement of intake and exhaust ports upon the stator, whereby maximum power and smooth 10 and even operation of the engine will be insured.

Another object of the invention is to provide an internal combustion engine of the rotary type, in which the only valves required are the intake valves, and these valves may be of the ordinary type, the invention therefore obviating the employment of expensive valve units, and complicated means for actuating the valves as well as the inconvenience and expense attending replacement or regrinding of the valves.

A further object of the invention is to provide in an engine of the type referred to, a novel arrangement of the cylinders and pistons of the rotor unit of the engine, and means for automatically effecting movement of the pistons, in proper order, in a manner to obtain the maximum benefit from the explosion of the charge delivered to the cylinders, without the necessity of resorting to the use of a crank shaft and connecting rods.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view in side elevation of the internal combustion engine embodying the invention.

Figure 2 is a vertical sectional view taken in a plane at right angles to the axis of the rotor of the engine.

Figure 3 is a sectional view taken substan-

tially on the line 3—3 of Figure 2 looking in the direction indicated by the arrows.

Figure 4 is a view in end elevation of one of the cylinders of the engine.

Figure 5 is a view in elevation of one of the cylinders looking at the advancing side thereof.

Figure 6 is a detail sectional view illustrating a packing means for establishing fluid-tight fit of the cylinder heads against the annular body of the stator.

The stator of the engine comprises a hollow annular body indicated by the numeral 1 and spokes 2, which radiate from bearings 3, are secured at their outer ends by bolts 4, to the opposite sides of the body 1, the bearings 3 constitute, in fact, bearings for the rotor unit of the engine and this unit will presently be specifically described.

In the embodiment of the invention illustrated in the drawings, the engine is of the four cylinder type, and in accordance with the principles of the invention, the stator body is formed at equidistantly spaced points in its circumference with three inlet ports 5

and fitted into each inlet port is the intake end of an intake valve casing 6 provided interiorly at its inner end with a valve seat 7 to accommodate the head of a check valve 8, a spider 9 being provided within the casing 6,

as usual, and a spring 10 being arranged upon the stem of each valve and bearing against the spider and against the head 11 at the outer end of the stem, so that the valves are normally held in a closed position.

The body 1 of the stator is further formed with three exhaust ports 12, each arranged between two adjacent ones of the intake ports 5, and these exhaust ports are equidistantly spaced about the circumference of the body of the stator.

An intake manifold 13 is connected at each side of one of the intake valve casings, and these sections of the manifold, as a whole, are connected at their other ends to the casings of the other intake valves, the manifold sections extending concentrically with respect to the stator, and a supply main 14 for the gaseous fuel for the engine is placed in communication with the first mentioned one of

70

75

80

85

90

100

the intake valve casings as shown in Figures 1 and 2 of the drawings.

An exhaust manifold, indicated by the numeral 15, is placed in communication at its ends with two of the exhaust ports 12, and intermediate its ends is in communication with the third exhaust port, and the outlet pipe for the exhaust, which pipe is indicated by the numeral 16, is led from the manifold at this point. Spark plug sockets 17 are provided upon the interior of the stator body 1. Each of the spark plug sockets 17 is located a definite distance, and spaced from the adjacent exhaust port 12 and the adjacent inlet port 5, and somewhat nearer the exhaust port, in the direction of rotation of the rotor unit, and spark plugs 18 of the ordinary type are fitted in these sockets. At this point and particularly by reference to Figure 3, it will be evident that the stator body and the spokes 2 and bearings 3 are stationary.

The rotor unit comprises a central body indicated in general by the numeral 19, and this body comprises side plates 20 which are formed integral with or fixed upon the inner ends of relatively short shafts 21 rotatably mounted in the bearings 3, a series of plates are each formed to provide a portion 22, which is secured in any suitable manner to the inner end of each cylinder 23, this end of each cylinder, indicated by the numeral 24, being of rectangular form, and each plate further comprises a portion 25, which extends at an obtuse angle to the portion 22, and is secured at its end to the opposite side of the head 24 of the cylinder in rear of the first mentioned cylinder, in the direction of rotation of the rotor.

In this manner a polygonal and completely closed casing is provided to house parts which will presently be described, and in order that the heads 20 may be securely held and connected with the inner ends of the cylinders to properly brace the cylinders, bolts 26 are secured through the portions of the margins of the heads 20 which extend along the opposite sides of the inner heads 24 of the cylinders, these heads 20 being of a marginal contour to correspond to the successive ones of the plates 22 throughout the series of plates.

Each cylinder, at its outer end, is formed with an arcuate head 27 which has parallel sides and is of a width somewhat less than the width of the wall of the body 1 of the stator. The curvature of the cylinder heads 27 corresponds to the curvature of the surface of the stator body 1 and therefore the outer sides of these heads 27 are adapted to travel freely and yet snugly in contact with the inner surface of the said body 1. In order that a fluid-tight connection may be provided between the stator body 1 and the heads 27, each head is formed in its outer face with a circular groove 28 and a circular packing ring 29 is

seated in the groove and springs 30 bear against the inner side of the ring so as to hold the same in firm engagement, at its outer side, against the inner side of the stator body 1.

The pistons which operate in the cylinders are indicated by the numeral 31 and a compression spring 32 is arranged within each cylinder and bears at its inner end against the head 24 of the respective cylinder, and at its outer end against the piston head 31, the piston rods, being indicated by the numeral 33, and the rods of the pistons, each of oppositely located ones of the cylinders are connected pivotally, at their outer ends, as at 34, to the opposite ends of a rock lever 35, and these rock levers for the two pairs of pistons are arranged in crossed or intersecting relation and mounted upon a pin 36, which is seated at its ends in bearing sockets 37 formed centrally in the plates 20, and therefore in axial alignment with the shafts 2. These rock levers are free to rock upon the pin 36, and it will be evident, by reference to Figure 2 of the drawings, that when the piston head in one of the cylinders is forced inwardly, on the ignition stroke, the lever arm 35 to one end of which the corresponding piston rod is connected will be rocked so as to exert a pull upon the diametrically opposite piston and move the same inwardly in the respective cylinder.

While the engine when once set in motion and operating through the ignition of the explosive charge, will operate automatically and continuously, I have found it desirable to provide means for positively effecting rocking of the rock levers 35 and reciprocation of the respective pistons in the respective cylinders, independently of firing of the explosive charge taken into each cylinder by way of the intake valve 6, and this means comprises a series of six cams 38 which are formed upon the inner surface of the stator body 1 at one side of the rotor and, in a four cylinder engine, of this type, three of these cams will be located each adjacent a respective one of the spark plugs 18 and the other three cams will be located near the intake ports of the intake manifold 13 but slightly in rear thereof, in the direction of rotation of the rotor, the distance being determined by the distance between the inner side of the wall of the cylinder and the forward side of the roller 46 to be presently further described. One of each two oppositely positioned or companion cylinders has its rear side, considering the direction of rotation of the rotor, formed with a boss 39, and a rod 40 of rectangular cross sectional contour is slidably mounted in a similarly formed bore 41 in the said boss 39, and connected to the inner end of each rod is the outer end of a link 42, the inner end of which link is pivotally connected as at 43 to the respective lever arm 35 between the pin 36 and the adjacent

outer end of said lever arm. Each of the rods 40 is provided at its outer end with a laterally right angularly extending supporting portion 44 provided at its outer end with 5 a yoke 45 in which is mounted a roller 46, and these rollers travel against the inner surface of the stator body 1, and ride successively over the said cams 38.

As the rotor unit 19 is turned the roller 46 10 comes in contact with the cams 38 and this forces a set of the pistons 31 toward the center of the rotor at this time one of the pistons 31 is at intake position and its mating piston is at the firing point. A charge of 15 gas is taken into the cylinder of the first mentioned piston and when the cylinder has passed the intake port the cylinder is closed by the wall of the stator by the action of the spring 32 the charge in the said cylinder is 20 compressed and the charge in the cylinder which is at the firing point is exploded thus the pistons move inwardly. The pistons 31 move inwardly and through the springs 32 the power is transmitted to the cylinder 25 heads 24. By the impulse of power at this point the rotor unit is caused to turn. The heads 24 are disposed substantially tangentially to the rotor. The pistons drive the cranks on the shaft at a tangent which increases as the pistons work in and out. The 30 rotor unit is considered as a circular body and the heads 24 are disposed substantially tangent to said circular body and thus the rotor unit is made to revolve.

35 The operation of the engine will be readily understood by reference to Figure 2 of the drawings and in this figure the cylinder at the right of the figure has been fired and the piston in the cylinder at the left and opposite 40 to the first mentioned cylinder is at the beginning of its intake stroke, due to the connection between these two companion pistons; likewise, the lower cylinder in Figure 2 is in communication with the exhaust manifold 45 16 and the piston in the companion cylinder at the top of Figure 2 is at an intermediate point in its compression stroke, due to the connection between these two companion pistons.

50 It will be evident therefore that there will be practically a continuous firing of the cylinders so that the rotor body 19 will have imparted thereto, a substantially continuous rotary motion at a uniform speed. This motion, of course, being transmitted to the shafts 55 21. It will also be observed by a comparison of Figures 1 and 2 and by reference to the above description of the relative positions of the pistons that the engagement of the rollers 46 of the respective pistons with the successive cams 38 is in consonance with such movement of the pistons as would take place, if these rollers and cams would not be present, but, in starting the motor, the rotor may be 60 65 rotated by any suitable starting of the device

so as to set the engine in full operation. It will be understood, however, that the engagement of the rollers with the cams will effect, in a positive manner the properly timed motion of each respective piston. It will 70 further be evident that inasmuch as the cylinders 23 are disposed chordally with respect to the circumference of the stator, the combustion space between each piston head and the body of the stator is of such form and 75 such capacity as to insure of the most effective action of the explosive mixture on the firing stroke of each piston.

In order that lubricant may be supplied in a suitable quantity, to the outer surfaces of the heads 27, from the casing of the rotor, a strip 47 of packing material is secured in any suitable manner to the rear side of each of the said heads, and a small conduit 48 is arranged to extend between each outer wall 80 25 of the casing 19 and a head 27, the conduit, at its outer end having an extension 49 which is welded or otherwise secured to the inner side of the respective head and it will be evident that through centrifugal force, lubricant 85 will be caused to flow through these conduits in sufficient quantities to lubricate the surfaces of the heads and the inner surface of the annular wall 1 of the casing of the stator, a greater or less quantity of this oil being also 90 95 delivered into the cylinders 23 so as to lubricate the pistons.

It will be understood, that, in the operation of the engine, the springs 32 serve to 100 actuate the respective pistons on the compression and exhaust strokes of the pistons of each unit.

What I claim is:—

In an engine, a stator comprising an annular body provided at intervals with inwardly disposed cams, a rotor journaled in the stator, cylinders mounted upon the rotor and having ends closed by the stator, the stator having ports with which the cylinders communicate at intervals, pistons slidably in the cylinders, cross arms mounted upon the axis of the rotor for rocking movement thereon and connected with all of the pistons, rods connected with certain of the cross arms and disposed along certain of the cylinders and rollers carried by the rods and adapted to engage the cams successively.

In testimony whereof I affix my signature.
MARLIN S. CROSSLEY.
